UNITED STATES PATENT OFFICE.

WILLIAM J. CHENOWETH, OF DECATUR, ILLINOIS.

SURGEON'S OPERATING EXTENSION-TABLE.

SPECIFICATION forming part of Letters Patent No. 246,599, dated September 6, 1881.

Application filed March 12, 1881. (Model.)

To all whom it may concern:

Be it known that I, WILLIAM J. CHENOWETH, a citizen of the United States, residing at Decatur, in the county of Macon and State of Illinois, have invented a new and useful Improvement in Surgeons' Operating Extension-Tables, of which the following is a specification.

My invention relates to an improvement in surgeons' operating extension-tables; and it consists, first, in the use of a frame or box having a folding top or leaves hinged together and pivoted on bars so as to bring the center of the fold in the center of the frame when the leaves are open; second, the use of extra supporting devices opening out of the ends of the frame to give an additional support to the leaves; and, third, the use of an adjustable end piece to one of the leaves and the devices for operating the same. I attain these objects by the mechanism illustrated in the accompanying drawings, in which—

Figure 1 is a side elevation, showing top or leaves closed. Fig. 2 is a longitudinal vertical section on the line $x x$, Fig. 3; and Fig. 3 is an end view, showing the end support to the leaf.

A is a box-frame.

B B' is the folding top, hinged at C C. The lower part, B, has pivoted to it, on the inside of the box-top, a bar, D, which is also pivoted on the inside of the frame. The underleaf, B, is provided with the end piece, E, which has two arms, e e, pivoted to the inside of the part B, so that it may be raised up to fill the opening in the end of each of the leaves B and B'. When it is closed, as shown by dotted lines in Fig. 1, the incline pieces e' e', Fig. 2, are secured to the inside of the frame A in such a manner as to raise the end piece, E, automatically when the leaves are closed. The object of this end piece being operative is to admit of a mattress being placed on the leaves without dividing it in two parts, as a division at that place is objectionable.

F F' are parts, pivoted at f, which form panels at the ends of the frame A when closed, and when raised up serve as supports to the projecting ends of the leaves through the medium of the bar G, pivoted at g and having its lower end notched, so as to engage with the frame at a and retain it in position, as shown in Fig. 2.

I is a false bottom or cover to the drawers J

J, on which the bars G G slide inside the frame when the parts F are closed, as represented in Fig. 1 by dotted lines.

H is a bottom to the main body of the frame 55 or box A, and forms a receptacle for pillows and other covering of the bed.

The device operates as follows, viz: The top is swung over to the left on the pivoted bars D D, the center of the cover or leaves coming 60 in the center of the frame. The upper part, B', opens to the right. The parts or braces F F are opened out and upward, forming supports to the top B B'. As the leaves are moved or swung to the right the end E, being removed from the support of the beveled pieces e' e', drops, as shown. To close, the parts F F are replaced in the frame and the top closed together and moved to the right, the end E being raised up by contact with the beveled 70 pieces e' e'. This top may be used, without being made like a box, for a mattress by simply having the two parts B B' a flat leaf and hinged together, and the lower part, B, provided with lugs similar to those shown at F in 75 Fig. 2, to which the swinging bars D D may be pivoted.

What I claim as my invention, and desire to secure by Letters Patent, is—

1. The hinged top B B', provided with the 80 pivoted arms D D, in combination with the frame A for opening, closing, and extending the table, substantially as shown and described.

2. The parts F F, pivoted at f, and the pivoted and notched bar G, in combination with 85 the hinged top B B' and frame A, substantially as shown and described.

3. The end E, with the pivoted bars e e, in combination with the hinged top B B', frame A, and inclined pieces e' e', substantially as 90 shown and described.

4. The combination of the hinged top B B' and braces F F with the frame A, substantially as shown and described.

5. The combination of the hinged top B B', 95 braces F F, end E, and inclines e' e' with the frame A, substantially as shown and described.

WILLIAM J. CHENOWETH.
